CANTEEN

James W. Bush, Hightstown, N.J., assignor to Boy Scouts of America

Filed May 12, 1972, Ser. No. 252,960

Term of patent 14 years

Int. Cl. D9—01

U.S. Cl. D9—175

FIG. 1 is a front perspective view of a canteen embodying my new design;

FIG. 2 is a rear perspective view; and

FIG. 3 is a cross-sectional view taken on line 3—3 of FIG. 1.

I claim:

The ornamental design for a canteen, as shown.
